UNITED STATES PATENT OFFICE.

RICHARD HAMMERLY, OF NEW YORK, N. Y., ASSIGNOR OF ONE-HALF TO FRANK E. TILLY, OF WOODHAVEN, NEW YORK.

AUTOMATIC TRAIN-STOP.

1,103,763.

Specification of Letters Patent. Patented July 14, 1914.

Application filed September 13, 1913. Serial No. 789,631.

To all whom it may concern:

Be it known that I, RICHARD HAMMERLY, a citizen of the United States, and a resident of the city of New York, Woodhaven, borough of Queens, in the county of Queens and State of New York, have invented a new and Improved Automatic Train-Stop, of which the following is a full, clear, and exact description.

10 My invention has for its object to provide an automatic train stop having a depending arm on a locomotive for engaging trips at the side of the track to operate a signal and a signal member for engaging a finger on a shaft connected with a brake valve so that should the locomotive pass the signal when in danger position the trip will operate the brakes on the locomotive through the finger with which it will engage. Independent 15 means are provided for operating the brakes at the will of the engineer.

Another object of the invention is to provide a cylinder in communication with the brake cylinder and having a piston operable 20 by an increase of pressure in the cylinder, the piston operating a rack which engages a pinion secured to the stem of a rotary throttle valve so that the throttle valve will be automatically closed when the brakes are 25 applied.

Still another object of the invention is to provide the trips in pairs with means for raising the far trip, the signal member, and setting the signal at danger when the near trip is depressed, and for raising the near trip, lowering the signal member and changing the signal when the far trip is depressed.

Still other objects of the invention will appear in the following specification in 30 which the preferred form of my invention is disclosed.

In the drawings similar characters of reference indicate corresponding parts in all the views in which—

45 Figure 1 is a diagrammatic view showing how the members are assembled and are disposed in the locomotive; Fig. 2 is an enlarged fragmentary sectional view showing the means on the locomotive for operating the valve leading to the brake cylinder; Fig. 3 is a sectional view on the line 3—3 of Fig. 2; Fig. 4 is a sectional view showing the means for closing the throttle valve with an increase of pressure in the brake cylinder; Fig. 5 is a perspective view showing the 50 positions of the signal, the signal member

and the trips on the side of the track as well as their construction and their connections, and Fig. 6 is an enlarged sectional view on the line 6—6 of Fig. 5.

By referring to the drawings it will be seen that a sleeve 5 is mounted for rotating in a bearing 6 on the locomotive and that disposed in this sleeve 5 there is a shaft 7, there being an angular recess 8 at the bottom of the sleeve 5 in which a projection 9 on a shoe 10 is normally disposed. It will be understood that when the shaft 7 is raised to the position shown in Fig. 2 of the drawings that the projection 9 on the shoe 10 will engage the projection 11 on the side of the recess 8 so that the sleeve 5 will rotate with the shoe 10 and the shaft 7. The shaft 7 is normally held in this position by means of an arm 12 having a recess 13, the arm 12 normally engaging at its recess 13 a collar 14 on the sleeve 5. The arm 12 is supported when in this position by a flange 15 which is secured to the locomotive. At the top of the shaft 7 there is a hand-wheel 16 by 60 which the shaft 7 may be rotated by hand when desired. Extending radially from the shoe 10 there is a finger 17 with which the signal member 18 is adapted to engage when the signal member 18 is raised to the position shown in Fig. 5 of the drawings, which serves to turn the shaft 7 and with it the sleeve 5 so that the gear wheel 19 on the sleeve 5 will rotate the gear wheel 20 on the valve stem 21 of the valve 22, this valve 22 commanding communication through the pipe 23 leading from a supply of fluid under pressure to the brake cylinder 24.

It will be understood that when the sleeve 5 has been rotated in the manner described 65 that it will open the valve 22 in the manner stated to permit air under pressure to flow to the brake cylinder 24 thereby applying the brakes. The pipe 24 is disposed around the pipe 23 at the valve 22 and is connected 70 with the pipe 23 at 25 and 26 so that the engineer may by means of a hand valve 27 permit the air under pressure to flow to the brake cylinder 24 to apply the brakes independent of any movement of the sleeve 5. 75 Connected with the pipe 24 there is a pipe 27 which leads to a cylinder 28 having a piston 29 so that the piston 29 will be moved to the right of the cylinder 28 when the air under pressure is permitted to flow to the 80 brake cylinder, this movement to the piston 29 serving to close the throttle valve 30 by

means of the piston rod 31 which has a rack 32 meshing with the piston 33 on the valve stem 34 of the rotary throttle valve 30. A lever 35 is also secured to the valve stem 34 so that the throttle valve 30 may be operated manually when desired. The piston 31 extends through an opening 36 in a piston head 37 with which the cylinder 28 is provided all in the usual manner. At 10 the right of the cylinder 28 there is an orifice 38 through which the right hand side of the cylinder 28 may communicate with the atmosphere. The left of the cylinder 28 has an opening 39 in which is secured 15 a pipe 40 having a valve 41, by means of which the engineer is permitted to reduce the pressure at the left of the cylinder 28, the pipe 27 and the brake cylinder 24 of the pipes leading from the said brake cylinder 24 to the pipe 27. In the manner described 20 the rotary movement of the sleeve 5 by means of the signal member 18 and the finger 17 not only serves to permit the flow of a fluid under pressure to the brake cylinder 24, but this fluid under pressure also flows 25 to the cylinder 28 moving the piston 29 to the right to close the throttle valve 30 for shutting off steam to the locomotive the same time that the brakes are applied.

30 The signal member 18 is disposed vertically in a guide-way 42, the signal member below the guide-way 42 having a rack 43 which meshes with a pinion 44 secured to a stud 45 journaled in a frame member 46, 35 a member 47 with arms 48 and 49 being also secured to the stud 45. The arm 48 is connected with an arm 50 secured to a stud 61 by means of a rod 52, this stud 51 being journaled in a bearing in the frame 46 and 40 being secured to a pinion 53 with which meshes a rack 54 which extends up through a guide-way 55 in a plate 56 and to which the trip 57 is secured, this trip 57 being provided with a roller 58 with which an arm 59 on the locomotive is adapted to engage. The arm 49 on the member 47 is connected with the arm 59 on a member 60 by means of a rod 61, the member 60 being secured to a stud 61^a and to this stud 61^a 45 there is mounted a pinion 62, the stud 61^a being journaled in the frame member 46. Meshing with the pinion 62 there is a rack 63 which extends up through a guide-way 64 in a plate 65 and carries the trip 66 having a roller 67. Another arm 68 on the member 60 is connected by a rod 69 with a crank 70 on a shaft 71, this shaft 71 being journaled in a bearing 72 and having a 50 second crank 73 which is connected with a semaphore 74 by means of a rod 75.

With the movement of the locomotive along a track the finger 17 will strike the signal member 18 when the signal member

18 is raised to shut off the steam in the locomotive and apply the brakes, but should the signal member 18 be lowered the locomotive will pass to the trip 57 which is raised when the signal member 18 is lowered and the arm 59 will engage the trip 57 to raise the trip 66, the signal member 18 and 65 to move the semaphore 74 to the position shown in Fig. 5 of the drawings. With the continued movement of the locomotive, the arm 59 will strike the roller 67 on the trip 66 to press down the trip 66 which by 70 means of the pinion 62 the member 60 the rod 61, the member 47 and the pinion 44 will lower the signal member 18 and will by means of the rod 52, the arm 50 and the pinion 53 raise the rack 54 of the trip 57. 75 The movement of the member 60 will also by means of the rod 69 rotate the shaft 71 to lower the semaphore 74, this taking place when the locomotive with its train has moved out of the block. 80

Claims:

1. In an automatic train stop, two trips spaced apart and each provided with a rack, a pinion with which one of the racks meshes, a pinion with which the other rack meshes, 90 two arms secured to the first pinion, a signal, means connecting one of the arms with the signal for operating the latter, a signal member having a rack, a pinion meshing with the last mentioned rack, two arms secured for moving with the last mentioned pinion, means connecting the other of the first mentioned arms with one of the second mentioned arms, an arm secured to the second mentioned pinion and means connecting 100 the other of the second mentioned arms with the arm on the second mentioned pinion.

2. In an automatic train stop, two trips, a signal, a signal member, means connecting one of the trips with the signal and the signal member and independent means connecting the signal member with the other trip for the purpose specified. 105

3. In an automatic train stop, two trips having racks, a signal member having a 110 rack, a signal, pinions meshing with the racks and provided with arms, means connecting an arm on a pinion at one of the trips with the signal and with an arm on the pinion at the signal member and means 115 connecting an arm on the pinion at the signal member with an arm on a pinion at the other trip.

In testimony whereof, I have signed my name to this specification in the presence of 120 two subscribing witnesses.

RICHARD HAMMERLY.
